(57) CLAIM

The ornamental design for a doll body as shown and described.

DESCRIPTION

FIG. 1 is a front view of the first embodiment of the doll body.

FIG. 2 is a left side view thereof;

FIG. 3 is a rear view thereof;

FIG. 4 is a right side view thereof;

FIG. 5 is a front view of the second embodiment;

FIG. 6 is a left side view thereof;

FIG. 7 is a rear view thereof; and,

FIG. 8 is a right side view thereof.

The broken lines showing of the doll head is for the purpose of illustrating portions of the article that forms no part of the claimed design.
